UNITED STATES PATENT OFFICE.

OSCAR S. TENLEY, OF DUNBAR, WISCONSIN.

FOLDING TABLE.

1,213,976.

Specification of Letters Patent. Patented Jan. 30, 1917.

Application filed January 26, 1916. Serial No. 74,358.

To all whom it may concern:

Be it known that I, OSCAR S. TENLEY, a citizen of the United States, residing at Dunbar, in the county of Marinette and State of Wisconsin, have invented certain new and useful Improvements in Folding Tables, of which the following is a specification.

This invention relates to improvements in folding tables, one object of the invention being the provision of a table of this type, in which the top is composed of a plurality of hingedly connected leaves, and is provided with a pivotally mounted brace at each end, whereby the leaves may be permitted to fold when the braces are parallel to the longitudinal extent of the leaves, or they will be held flat when the braces are at right angles to the longitudinal extent of the said leaves.

10 A further object of the invention is the provision of a novel arrangement of mounting the foldable legs that will not interfere with the swinging of the braces, and which provides legs that when folded will fit in parallel relation and flush with the underside of the leaves carrying the two pair of legs.

A still further object of the invention is the provision of a folding table, which is simple in construction, durable, readily and easily folded and unfolded, strong, and inexpensive in manufacture, as well as thoroughly efficient and practical in use.

With these and other objects in view, the invention consists in the features of construction, combination and arrangement of parts as will be hereinafter fully described, illustrated in the accompanying drawings, and pointed out in the claims hereunto appended.

In the accompanying drawings, Figure 1, is a fragmentary perspective view taken from below at one end of the table constructed in accordance with the invention. Fig. 2, is a similar view looking from below toward the opposite end of the table. Fig. 3, is a bottom plan view with the legs extended, and the braces in bracing position. Fig. 4, is a similar view with the legs folded, together with braces swung into folding position. Fig. 5, is a view showing the leaves of the top of the table folded. Fig. 6, is an end view thereof.

Similar reference characters indicate corresponding parts throughout the several views in the drawings.

55 Referring to the drawings in detail, the table comprises a top 10, which as here

shown is composed of the two outer leaves 11, and 12, the intermediate leaf 13, and the two leaves 14, and 15, respectively, all of the leaves being connected together by the hinges 60 16, so that the leaves may be folded as shown in Figs. 5 and 6, of the drawings, or said leaves may be extended as shown in the other views in said drawings. The leaf 14, is of less width than the leaf 15, so as to permit 65 the proper folding of the top of the table with the legs and braces thereof.

Swingingly connected at one end to the under side of each leaf 11, and 12, is a brace 17, there being two of these braces, which are adapted to engage in locking members 19, mounted on the leaves 11, and 12, when said braces are moved transversely of the leaves for holding the latter against folding movement. The brace on the leaf 11, co- 75 operates with the locking member on the leaf 12, while the brace on the leaf 12, co-operates with the locking member on the leaf 11, so that the braces 17, will be in parallel relation to each other, when lying transversely 80 of the leaves or at right angles to the longitudinal extent thereof. The locking members 19, are constructed in the form of pivoted hooks, so that they may be swung to release the braces 17, when desired.

The braces 17, are formed with notches 18, in their faces next to the leaves of the top to avoid any interference by the fastenings for the legs of the table, hereinafter described.

90 Connected by means of hinges 20, two to each of the respective leaves 11, and 12, are swinging legs 21, each of which is provided with elongated grooves 22, and 23, longitudinally disposed therein, while swingingly connected by means of the fastenings 24, and 25, respectively to the legs at the upper ends of the respective slots 22, and 23, are the metal braces 26, and 27, respectively. The braces 26, when folded upon the legs 100 will fit within the slots 22, which form seats therefor, while their free ends when the legs are extended will fit in the fastenings 28, and thus cause the braces to hold the legs perpendicular for supporting the 105 top of the table.

The braces 27, will fit within the other slots 23, when the same are folded or will engage the fastenings 29, to assist in holding the legs extended and perpendicular 110 to the top of the table.

Mounted on the under side of the leaves

13, and 15, are the hook like keepers 30, which receive the braces 17, when swung transversely of the leaves of the top so as to hold the said leaves 13, and 15, in the same plane with the leaves 11, 12 and 14, and thereby retain the top firmly in position for use on the setting up of the table. The grooves 31 are provided in each leg so that the staples 28 may fit therein when the legs 10 are collapsed.

It will be noted that the brace carried by the leaf 11, is pivoted nearer the outer edge of the leaf than that one carried by the leaf 12, the one carried by the leaf 12, being mounted between the legs 21, carried by such leaf 12. This is done so that leaves, braces and legs may assume the position as shown in Figs. 4, 5, and 6, of the drawings, and thus will easily permit the folding of the leaves of the top, as illustrated in Figs. 5, and 6, of said drawings. It will also be noted that the legs must be dropped to supporting position before the braces 17 can be moved to support the leaves, and that the braces 17 are sufficiently near and thick enough to prevent the legs collapsing before the wire braces are hooked. It will also be noted that when the legs are folded upon the carrying leaves, the braces cannot be 30 extended.

What I claim, as new, is:—

1. A folding table, including a top composed of a plurality of hingedly connected leaves, two braces, one pivotally connected to the under side of each outer leaf, one being pivoted nearer the outer edge than the other and both being mounted for movement parallel to and at right angles to its carry-

ing leaf and for passage beneath the other brace carrying leaf when the top is extended, means for holding the braces extended, two pairs of legs hingedly connected, one pair to each outer leaf, one leg of each pair being within the pivotal point of its brace and all legs nearer the respective ends of the outer leaves than the braces, whereby the braces when extended limit the folding movement of the legs but permit the folding of the legs upon and parallel to the longitudinal edges of the carrying leaves when the top is folded, and means for locking the legs extended.

2. A folding table, including a top composed of five leaves hingedly connected together, whereby when folded the middle leaf and one of the outer leaves will be parallel and form the exterior members, while the other outer leaf will be in parallel but incased, the other leaves being in parallel to each other and forming outer members at the opposite sides of the table to the middle and outer leaves, two braces, one pivotally connected to each outer leaf for movement in parallel and at right angles thereto, each of said braces being sufficiently long to extend beneath both outer leaves when the top is extended, and four legs, two legs being hingedly connected to each outer leaf beyond the braces, whereby the braces can be collapsed and extended when the legs are extended, but are prevented from extension when the legs are folded upon the carrying leaves.

In testimony whereof I affix my signature.

OSCAR S. TENLEY.
